FIRE EXTINGUISHER

Kenneth B. Covert, Marinette, Wis., assignor to Safe, Incorporated, Marinette, Wis., a corporation of Wisconsin

Filed Aug. 24, 1956, Ser. No. 606,058

5 Claims. (Cl. 169—31)

This invention relates to fire extinguishers and more particularly to a novel dry powder fire extinguishing composition adapted to be expelled from a pressurized container.

There has long been recognized in the fire extinguishing industry the need for an improved, hand-sized dry powder-type fire extinguisher which is useful in homes, industrial locations, in the armed services and particularly in automobiles and other motor vehicles. Such a fire extinguisher should desirably be safe to use for many different types of fires in order that it attain a wide scope of use.

The National Board of Fire Underwriters has classified incipient fires into three classes:

Class A fires.—Those in ordinary combustible material where the quenching and cooling effects of quantities of water or solutions containing a large percentage of water are of primary importance.

Class B fires.—Those in oils, greases, flammable liquids, etc., where the blanketing or smothering effect of the extinguishing agent is of greatest importance.

Class C fires.—Those incipient fires in electrical equipment where the non-conducting property of the extinguishing agent is of prime importance. Dry powder chemical extinguishers are generally rated for classes B and C and will reduce a class A blaze to embers which can be easily controlled with water.

The biggest problem facing users of dry powder chemicals for fire extinguishing has been the efficient application of the chemical to the fire area. In this regard both the range of the fire extinguisher and the area or pattern which it covers are of prime importance. The range of the fire extinguisher should be sufficient so that the user need not approach the fire too closely and should be reasonably consistent and constant so that the stream of extinguisher will not overshoot or undershoot the fire area. The pattern of the fire extinguisher stream is also most important for the reason that it is desirable to place as much as possible of the fire extinguishing powder in the fire area.

To utilize dry powder chemicals more effectively, attempts have been made to expel a liquid-like slurry of the powder in a propellant such as a "Freon" from a pressurized container. The thought behind this attempt was that, after the slurry was expelled from the container, the propellant would evaporate leaving a dry powder residue. This slurry was thought to be somewhat in the nature of an aerosol in which a liquid is expelled as an emulsion in a "Freon" propellant. After the latter evaporates, the liquid residue remains. When this theory was applied to powder-type fire extinguishers, however, it was found that, while a substantial amount of the powder was expelled and directed into the fire area, the fire extinguishing characteristics were poor and, in fact, were no better than the characteristics obtained with the "Freon" propellant alone. It was found that the "Freon," generally about 90% of the total weight of the mixture, was not evaporating rapidly enough and

2

was itself acting as the fire extinguishing agent. A further disadvantage in the slurry type of fire extinguisher was that it required a substantial amount of shaking before it could be used because the wet powder had a tendency to cake in the can.

Propellants, such as carbon dioxide, nitrogen, etc., which are gases at room temperature and at the pressures permissible in the containers of the type referred to herein have also been employed. The results obtained with these propellants are unsatisfactory since there is a strong initial blast or rapid discharge which rapidly falls off in intensity. As a result, a large part of the powder misses the fire area entirely and, more often than not, is not even expelled from the container.

It is an object of the present invention to provide a self-contained, single use, hand-size fire extinguisher which is efficient in its operation of projecting a large amount of a fire extinguishing powder into a fire area and with substantially complete discharge from the container.

Another object of the present invention is to provide a powder-type fire extinguisher which affords a smooth and steady discharge into a fire area, with a constant range and coverage pattern and without under-shooting or over-shooting the fire.

A further object of the present invention is to provide a powder-type fire extinguisher of the foregoing characteristics which is ready for use at all times without shaking or other preliminary treatment.

Still another object of the present invention is to provide a powder-type fire extinguisher of the foregoing type in which the powder in the container is not wet and when expelled, is ready for use as an effective fire extinguishing agent.

Still a further object of the present invention is to provide a powder-type fire extinguisher of the above type in which the most economical use of propellant is made while substantially all of the powder is discharged.

Other objects and advantages of the present invention will become apparent from the following detailed description, taken in connection with the accompanying drawings wherein:

Figure 1 is a graphical representation of the relationship between the percentage of the fire extinguishing powder discharged from a container and the weight ratio of the amount of fire extinguishing powder to the amount of propellant.

Fig. 2 is an elevation view, partly in section, of a dry powder fire extinguisher and showing its valve in a normally closed position.

While the invention is susceptible of various modifications and alternative constructions, a certain illustrative embodiment will be described below in detail. It should be understood, however, that there is no intention to limit the invention to the specific form disclosed but, on the contrary, the intention is to cover all modifications, alternative constructions and equivalents falling within the spirit and scope of the invention as expressed in the appended claims.

In accordance with the above objects of the present invention, it has been found that by employing a mixture comprising a powder of the type suitable for extinguishing fires and a critical amount of difluorodichloromethane (known by the trademark "Freon-12"), a volatile organic compound generally termed a propellant, that a highly efficient, improved fire extinguisher is produced. The two ingredients, mixed in critical proportions, are maintained in the container under a pressure such that the propellant is a saturated vapor at room temperature. There is, at the most, only a few droplets of liquid and substantially no wetting of the fire extinguishing powder. The mixed ingredients are confined at about the vapor pressure of the propellant, in a pressure-type container

which is provided with a nozzle opening controlled by a suitable, manually operated single-shot valve. When the valve is opened the pressure in the container is released and the powder is carried or propelled outwardly through the nozzle in a continuous steady stream which may be directed at a fire area.

For the most satisfactory discharge of powder from a container of the above type, an important relationship has been found to exist between the amount of dry powder and the amount of "Freon-12" propellant. I have found that if a given amount of powder is placed in a sealed container and an amount of "Freon-12" is added, so that the pressure resulting in the container is equal to the vapor pressure of "Freon-12" at room temperature and at the same time there is little or no wetting of the powder by the "Freon-12," that the most desirable conditions obtain for efficient and effective discharge of the powder into a fire area when the extinguisher is used. The results of my discovery are presented in Fig. 2, which shows an empirical relationship between the percentage of the powder discharged from the container and the weight ratio of the amount of powder to the amount of "Freon-12" propellant.

For example, in a can of the nominal 12 ounce size, having about 23 cubic inches of free space when empty, I employ about 12 ounces of dry powder such as sodium bicarbonate in finely divided powder form. On this powder charge I add a charge of 14 grams of dichlorodifluoromethane known as "Freon-12." This results in a pressure in the container of approximately 70 p.s.i. at about 70° F. No wetting of the powder is observed and, in fact, only one or two droplets of liquid "Freon-12" are observed to be present.

Upon discharging this composition by opening the single-shot valve on the container, I have found that I achieved a constant blast of powder having a range of about 8 feet, and covering an area of about 30 to 36 inches in diameter. Approximately 98% of the dry powder contents was discharged. This optimum amount of propellant added was found by placing the required amount of dry powder in a suitable container and adding the propellant. The propellant was added to the container of the powder until an amount was present which just indicated that there is a saturated gas in the container. It should be noted that I have attained a valuable added advantage of economy because I employ only a small amount of the most expensive ingredient, the propellant "Freon-12." By adding less propellant than heretofore was thought to be necessary, I have not only achieved improved operation, but have substantially reduced the cost of the extinguisher.

Through a series of experiments I have determined that a ratio of approximately 24 to 1 parts of powder per part of "Freon-12" propellant results in a maximum discharge of about 98% of the powder from the container. Stated in another way, such a ratio provides a propellant weight equal to 4 1/4% of the powder weight. In addition, the powder is expelled in a smooth, continuous stream lasting for about 5 to 7 seconds. This stream is confined to a relatively small area and may be directed to a specific fire area for obtaining the maximum coverage and fire extinguishing efficiency. The results of these experiments are presented in graphical form in Fig. 1.

I have further determined, as shown in Fig. 1, that the minimum desirable weight ratio is 18 parts of dry powder to one part of propellant (e.g. 18 to 1). Inversely restated, the propellant is by weight equal to 5 1/2% of the weight of the powder. Below this ratio the excess of propellant caused a substantial wetting of the powder with a resultant rapid drop-off in fire extinguishing efficiency. I have additionally determined that the maximum ratio should be about 40 parts of dry powder to one part of propellant (e.g. 40 to 1) and that above this ratio there was not enough propellant to discharge an economical

amount of powder from the container. The percentage discharge obtained at the 40 to 1 ratio was approximately 70% of the contents in the container, as shown in Fig. 1. The propellant at this ratio equals 2 1/2% of the powder weight.

When employing the optimum ratio of powder to propellant, namely 24 to 1, I observed that during the initial discharge of powder, from about 8 feet away from the fire, that a minimum of 70% of the powder goes into the fire area without requiring the user to move towards the fire. On the other hand when gaseous propellants are used in similar proportions, such as carbon dioxide and nitrogen, I found that the initial blast tended to over-shoot the fire area under similar circumstances and that less than 50% of the initial blast fell into the area.

I prefer to confine my composition in a pressurized container 10 of the type shown in Fig. 2 of the drawing. The container shown comprises a can having a body portion 12 and a suitable attached concave bottom wall 13. An outlet valve 15 is desirably secured in an opening in the top wall 16 of the can. Such a valve is described in more detail in Patent 2,785,838 issued March 10, 1957, on a co-pending application, Serial No. 462,639, filed October 18, 1954, and assigned to the assignee of the present invention. Briefly, this valve 15 comprises a dip tube 18 inserted and soldered into an aperture 19 in the can top 16 and extending in a gradually curved section towards one corner of the can.

A nozzle 20 is formed by the upper section of the dip tube which extends above the can top and is bent over at an angle from the horizontal to afford a smooth, uninterrupted passage with no abrupt changes in direction or cross-section. The valve 15 comprises a valve element 21 which seats on the lower end of the dip tube 18 and is held in place by the internal pressure in the can. The element 21 is actuated to the open position by a straight section of resilient wire or stem 22 disposed for most of its length within the dip tube 18. The upper end of the stem is fitted through a bore 24 in the external dip tube portion or nozzle 20. The upper end of the stem is preferably flattened out in nailhead fashion or provided with a suitable pushbutton 25. A protective cap 26 covers the valve and nozzle to prevent an accidental discharge. This cap is removed just prior to using the extinguisher.

To operate the valve, the can is grasped in the user's hand and the head of the stem is depressed. The axial motion transmitted through the stem wire forces the valve element out of the end of the tube and the resilient valve stem tends to straighten out and move the plug laterally so it cannot be reclosed. The can, when used with a composition having the ratios described according to the present invention and when held in about a 45° position, affords a maximum expulsion of the powder charge.

There has been described a new and useful novel fire extinguishing package which is efficient in its operation and adapted for extinguishing small fires by means of a dry powder chemical. With the high ratio of dry powder to "Freon-12" propellant used, substantially all of the chemical is discharged in a smooth stream to provide an efficient fire-fighting device. This improved fire extinguisher produces a smooth and steady discharge of dry powder fire extinguishing chemical affording an effective fire fighting device. This result is due to the heretofore unknown critical relationship between the amounts of propellant and dry powder used as fully described above. My improved fire extinguisher is handy and small, being dimensioned for grasping in the hand of the user. Accordingly, it is portable and especially well adapted for use in automobiles where gasoline fires are most likely to occur. The container is also adapted for mounting in convenient and strategic locations in a house or other building so that it is ready for instant and dependable use when an emergency arises.

By using only a small amount of "Freon-12" propellant in comparison to the amount of fire extinguishing powder, I have produced a powder type fire extinguisher having a number of important advantages. In particular, my fire extinguisher is a highly efficient, single-shot, bomb-like package capable of producing a continuous smooth and steady discharge of substantially all of the container dry powder into a fire area. Because only a small amount of propellant is used, my fire extinguisher is quite inexpensive to manufacture and can be sold at a low cost.

I claim as my invention:

1. A package comprising a pressure-type container having a valve-controlled opening charged with a fire-extinguishing dry powder and a gaseous propellant confined in the container under the vapor pressure of the propellant, the powder being sodium bicarbonate and the propellant being dichlorodifluoromethane in an amount from about 2½% to about 5½% of the powder by weight.

2. A package comprising a pressure-type container having a valve-controlled opening charged with a fire-extinguishing dry powder and a gaseous propellant confined in the container under the vapor pressure of the propellant, the powder being sodium bicarbonate and the propellant being dichlorodifluoromethane, the weight ratio of the powder to the propellant being in the range of from about 18-1 to about 40-1.

3. A powder-type fire extinguisher comprising a sealed vessel with a valve-controlled opening charged with sodium bicarbonate in the form of a finely divided dry

10

15

20

30

powder and gaseous dichlorodifluoromethane as a propellant the powder and the propellant being confined under the vapor pressure of the propellant and the propellant being in the vicinity of 4% of the powder dry weight.

4. A powder-type fire extinguisher comprising a sealed vessel with a valve-controlled opening charged with sodium bicarbonate in the form of a finely divided dry powder and gaseous dichlorodifluoromethane as a propellant, the powder and the propellant being confined under the vapor pressure of the propellant, and the weight ratio of the powder to the propellant being approximately 24-1.

5. A pressurized dry powder dispenser comprising a pressure-type container having a normally closed discharge orifice and charged with a finely divided dry powder and gaseous dichlorodifluoromethane, the powder and the dichlorodifluoromethane being confined under the vapor pressure of the latter with the amount of the dichlorodifluoromethane being from about 2½ to about 5½% of the powder by weight.
